UNITED STATES PATENT OFFICE.

IRA H. SPENCER, OF WEST HARTFORD, CONNECTICUT.

INTERNAL-COMBUSTION ENGINE.

Application filed October 14, 1922. Serial No. 594,500.

My invention relates to that class of engines in which a volatile fluid is ignited under compression in the cylinders, the invention in particular lending itself admirably 5 to an engine of the two cycle crank case compression type, and an object of my invention, among others, is the construction of an engine to produce maximum results in efficiency with a minimum expenditure of 10 power.

One form of engine embodying my invention and in the construction and use of which the objects herein set out, as well as others, may be attained, is illustrated in the accompanying drawings, in which—

Figure 1 is a view in side elevation of my improved engine.

Figure 2 is an end view of the same.

Figure 3 is a top view.

Figure 4 is a view of the end opposite to that shown in Figure 2.

Figure 5 is a view in central vertical longitudinal section through the structure.

Figure 6 is a view of a fragment of the 25 engine cut in horizontal section on a plane denoted by the dotted line 6 of Figure 5.

Figure 7 is a similar view on a plane denoted by the dotted line 7 of Figure 5.

Figure 8 is another similar view on a plane 30 denoted by the dotted line 8 of Figure 5.

Figure 9 is a view in vertical section on a plane denoted by the dotted line 9—9 of Figure 3.

Figure 10 is a view of a fragment of the 35 structure on a horizontal plane denoted by the dotted line 10 of Figure 5.

Figure 11 is a similar view on a plane denoted by the dotted line 11 of Figure 5.

All of the views from and including Figure 40 upwardly are on enlarged scale.

In the accompanying drawings the numeral 15 indicates the base section of my improved engine and it may be composed of any suitable material formed to shape in any desired manner, and it comprises in a single piece not only a supporting base for the cylinders, with a portion of crank chambers and bearings for the crank shaft, but also a pump and generator frame 16 embodying a 45 pump case 17 and a generator case 18. This 50 base section also includes as an integral part thereof a starter case 19 and laterally extending engine supports 20 located at each end of the section, together with a portion 55 of a fly wheel case, the supports 20 at this end of the structure preferably projecting from this case.

A pan section 22 of the engine is formed to provide a portion of the crank shaft bearings and crank chambers, and a section 23 of the fly wheel case constitutes one end of this section. Bottom closing plates 24, secured in place in any suitable manner, close a number of bottom openings into the crank 60 chambers, these openings being located opposite the cranks on a crank shaft 25 mounted in the crank shaft case, which case is composed of the base and pan sections of the structure.

This crank shaft case as a whole is of particular construction, it being divided into a number of crank chambers 26, walls of which closely enclose the cranks, the walls between adjoining crank chambers being quite thick and formed with openings 27—28 in the sections 15 and 22, respectively, the thickness of these walls being such as to provide suitable bearings for the crank shaft, and as shown in Figure 5 of the drawing. A fly 65 wheel 29 is secured to the crank shaft at one end within the fly wheel case, and a sprocket wheel 30 is secured at the opposite end of the crank shaft and is connected as by a sprocket chain with a sprocket element on the end of a pump and generator shaft 31 70 mounted in bearings in the pump and generator frame 16. A sprocket chain case 32 is removably secured to the end of the sections 15 and 22 to enclose the sprocket chain just hereinabove referred to. Balance segments 33, preferably two in number, are secured to squared portions of each crank at the crank shaft end thereof, these segments each being of a weight to counterbalance the crank, and they may be secured in place in 75 any suitable manner, as by a recess in the flat surface receiving the squared portion of the crank, and with screws passing thru the weights into the crank. In order to provide for maximum results in compression filling 80 segments 35, of an extremely light metal, different from that of which the segments 33 are composed, and corresponding in form thereto, are secured to the squared portions of the crank in a manner similar to that employed for securing the segments 33, the segments 35 lying on opposite sides of the connection for the piston rod 34.

The cylinder section 36 of my improved engine is secured to the top of the base section 15 with the cylinders in line with openings 37 through the top of the section 15, which openings establish communication between the crank chambers in which compression takes place and the lower ends of the cylinders. This cylinder structure comprises an outer wall 38 forming the entire side surfaces of the structure, and it also comprises inner or cylinder walls 39 within which the piston chambers 40 are inclosed. The outer wall incloses water chambers 41 and 42 at the bottom and top of the structure and comprising a portion of a water cooling system, the said outer wall also inclosing an inlet chamber and exhaust chambers 43-44 located vertically between said water chambers and within a bulge extending horizontally into the chambers, as shown in Figure 9. The inlet chamber extends from end to end of the structure, as shown in Figure 11, the cylinders rising through said chamber, and inlet passages 45 open thereinto from the side of the structure opposite the cylinders. A series of inlet ports 46 open from the inlet chamber into each of the cylinders for admission of fuel into the cylinders below the piston for compression purposes.

There is an exhaust chamber 44 appurtenant to each cylinder, as shown in Figure 10 with exhaust openings 47 from each of said chambers into an exhaust manifold 48, this exhaust manifold being integral with an inlet manifold 49, which manifolds consequently comprise an integral structure removably secured to the side of the engine, as shown in Figure 2 of the drawing. The inlet manifold communicates in any ordinary manner with a carburetor 50, and the exhaust manifold has a flange 51 for the attachment of an exhaust pipe.

The fluid used for ignition purposes is admitted in a manner common to devices of this class into the cylinders below the pistons, when the latter are at the upper limit of their movements, said pistons comprising the valves for controlling the inlet ports 46. From the compression chamber in the lower ends of the cylinders the ignition fluid flows to the transfer passages 52 formed in transfer ribs 53 extending from the top to the bottom of the cylinder section 36, jutting into the several water, inlet and exhaust chambers, as shown in Figures 6, 7, 10 and 11 of the drawings. These transfer passages open at the top of the structure into a transfer chamber in a cylinder head to be hereinafter described.

The wall of the cylinder section 36 is thickened on the side opposite the inlet and exhaust passages and openings, and conduits 54 are formed in said thickened portions of the walls for the flow of water through the

chambers 41 and 42, and as shown in Figures 7, 10 and 11 of the drawings. The chamber 41 communicates with a pump chamber 55 by means of registering openings in the top of the pump chamber and bottom of the chamber 41, as shown in Figure 9 of the drawings, and in order to promote effective circulation of the water a diaphragm 56 is located directly over the opening from the pump and extends horizontally about half way across the chamber appurtenant to each of the cylinders and partially surrounding such cylinders. This prevents the water from flowing from the pump directly upward on one side of the cylinders, but compels such water to traverse the chamber from one side to the other in its passage from the pump to water outlets 57 connected to the cylinder head. The pipes 57 may be connected to the cylinder head at a number of points and with a radiator, and the latter may be connected with a water inlet 58 at the bottom of the pump chamber (see Figure 2) in any well known and ordinary manner. The cylinder head 59 is removably secured to the top of the cylinder section 36, shallow transfer chambers 60 being formed in the lower part of the head and into which chambers the transfer passages 52 extend, as shown in Figure 8 of the drawings, there being one of these transfer chambers for each cylinder.

Admission ports 61 open from the transfer chambers directly into the tops of the cylinders, and the upper part of each cylinder is formed with a peripheral groove or recess comprising a direction passage 62 to ensure entrance of the fluid into the cylinder in a manner to produce maximum results.

A check valve 63 is employed to close each of the admission ports 61 and this valve is of particular construction in that it is of a concave shape on its upper side and is of a size substantially that of the cylinder. These valves are held to their seats as by springs 64 in valve spring pockets 65 in the upper surface of the cylinder head, there being a pocket for each cylinder and each pocket being closed by a cap 66. As the gas enters the cylinders the shapes of the valves and of the direction passages causes such gas to flow radially towards the center of the cylinder, and this prevents tendency of the fresh gas to mix with the burned gases lower down in the cylinder, with a result that efficiency in gas combustion is promoted.

A water chamber 67 extends from end to end of the cylinder head and communicates with the water chamber 42 by means of passages 68, as shown in Figure 6 of the drawings. The cylinder head is thus provided with a water cooling chamber surrounding the valve stems, and this is an advantageous feature of the cooling system.

5 A timing device 69 is mounted on the frame 16 and is operated as by means of a shaft extending downwardly through a post 70 and having a worm wheel in mesh with a worm on the shaft 31, the timing shaft, worm wheel and worm not being shown, as they will be readily understood by those skilled in the art.

10 I am aware that valves have heretofore been used in the tops of cylinders for admitting ignition fluid thereto, and I do not broadly claim such features, my present invention differing from those of the prior art in so sizing the valves that they will automatically control the inflow of fluid and admit the proper amounts under all conditions as to speed, it being noted that each valve is of a size in diameter substantially 15 that of the diameter of the cylinder thereby providing a maximum area for the action of pressure thereupon to open the valves and thereby enabling a spring of maximum stiffness to be employed for the purpose of accelerating the movements of the valve, all of 20 which contribute to the automatic action of the valve to regulate the flow of fluid in accordance with the rate of speed of the engine.

25 By employing a valve of this size with a direction passage in the wall of the cylinder at the upper end thereof, with corners properly shaped, the flow of fluid is so directed and controlled as to produce a uniflow engine with a minimum chance for the mixing 30 of the old and new gases.

35 In accordance with the provisions of the patent statutes I have described the principles of operation of my invention, together with the device which I now consider to represent the best embodiment thereof; but I desire to have it understood that the device shown is only illustrative and that the invention may be carried out by other means.

40 I claim—

45 1. An engine comprising a cylinder with appurtenant parts including means for compressing fluid, and a valve in the top of the cylinder adapted to be opened by compression of said fluid for admitting said fluid to the cylinder, said valve being of a size at least equal to the diameter of the cylinder to regulate the inflow of fluid to a degree depending upon the speed of movement of the piston.

50 2. An engine comprising a cylinder with appurtenant parts including a piston arranged to compress an ignition fluid, a valve in the top of the cylinder adapted to be opened by the compression of said fluid for admitting said fluid to the cylinder, said valve being of a size at least equal to the

diameter of the cylinder to regulate the inflow of said fluid to a degree depending upon the speed of movement of the piston, and a spring to accelerate the movement of said valve, said spring being located in a position accessible outside of the cylinder. 65

3. An engine comprising a cylinder with appurtenant parts including a piston arranged to compress an ignition fluid, said cylinder having an enlarged valve chamber forming a groove with curved walls, a valve located opposite said groove and of a size at least as large as the diameter of the cylinder, said valve being adapted to be opened 70 by compression of said fluid and said valve having its edge conforming in shape to the walls of said groove, and means for closing said valve. 75

4. An engine comprising a cylinder, a recess in the wall at the upper end of the cylinder forming a direction passage, said recess being larger in diameter than said cylinder, means for compressing an ignition fluid, and a valve movably mounted in the recess and 80 of greater diameter than the bottom of the latter, said valve and adapted to be opened by the compression of said fluid and acting in connection with said direction passage to direct flow of fluid into said cylinder. 90

5. An engine comprising a cylinder with appurtenant parts including a piston arranged to compress an ignition fluid, said cylinder having a recess in the side wall constituting a direction passage, and a valve 95 to regulate admission of fluid to the cylinder, said valve being of concaved shape on its upper surface and of a size at least equal to the diameter of the cylinder to direct flow of fluid to said direction passage. 100

6. An engine including a cylinder, an ignition fluid admission port in the upper end of the cylinder, an annular recess in the wall of the cylinder forming a direction passage for said fluid leaving the admission port, 105 said recess being larger in diameter than said cylinder, and a valve for the admission port movably mounted with its peripheral edge portion occupying a part of the recess, whereby all fluid leaving the admission port 110 must travel around the valve while passing through the direction passage.

7. An engine including a cylinder, an ignition fluid admission port in the upper end of the cylinder, an annular recess in the 115 wall of the cylinder forming a direction passage for said fluid, and a valve for the admission port concaved on its upper surface and movably mounted with its peripheral edge portion occupying a part of the recess.

IRA H. SPENCER.
